UNITED STATES PATENT OFFICE.

GEORGE H. HARVEY, OF PITTSBURG, PENNSYLVANIA, ASSIGNOR TO THE NATIONAL TUBE COMPANY, OF NEW JERSEY.

PIPE-THREAD PROTECTOR.

SPECIFICATION forming part of Letters Patent No. 642,324, dated January 30, 1900.

Application filed August 1, 1898. Serial No. 687,405. (No model.)

To all whom it may concern:

Be it known that I, GEORGE H. HARVEY, a citizen of the United States of America, and a resident of Pittsburgh, county of Allegheny, 5 State of Pennsylvania, have invented certain new and useful Improvements in Pipe-Couplers, of which the following is a specification.

My invention relates to couplers or thread-protectors for rods or pipes, having special 10 use as thread-protectors to engage with the threads of pipes or bars and protect the same from injury in handling or transportation, its object being to provide a cheap coupling or 15 protector suitable for use with the larger sizes of pipe and which can be produced at reasonable cost.

It consists, essentially, in a coupler or thread-protector having a series of ribs on its inner face, placed at equal distances apart, 20 and having screw-threads on the upper edges of such ribs.

To enable others skilled in the art to make and use my invention, I will describe the same more fully, referring to the accompanying 25 drawings, in which—

Figure 1 is a perspective view of a strip from which the protectors are to be formed. Fig. 2 is an end view showing the same bent into annular form. Fig. 3 is a longitudinal 30 section showing the same threads formed on the inner face of the ribs.

In said drawings, 1 is the flat strip of metal, having the ribs 2 formed on one face thereof, these ribs being placed at practically equal 35 distances apart and having open spaces 3 between the ribs. Such rolled strip is bent into annular form, as shown in Fig. 2, its ends being connected together in any suitable way, the ring or annulus so produced being thread-

ed in any suitable machine. The threading- 40 dies engage only with the faces of the ribs 2, cutting the threads 4 on the same, as shown in Fig. 3, the open spaces 3 between the ribs reducing materially the cost of tapping by reducing the surface to be tapped, while such 45 open spaces allow the taps to cool during the cutting of the thread and so extend their life. The coupling or protector so produced engages with the threads of the pipe or bar at short intervals and so forms a strong and rigid 50 coupling or protector, though of light weight, because of the ribs formed on the body, which provide for the bracing of the same and make it possible to form such body of light weight, while the threads are cut only upon the ribs 55 which engage at intervals with the threads of the pipe or bar and through the same, as well as the bodies of the ribs, give the necessary bracing.

What I claim as my invention, and desire 60 to secure by Letters Patent, is—

1. A coupler or thread-protector formed with an annular body portion having a series of ribs on its inner face set at substantially equal distances, the faces of said ribs being 65 tapped to form screw-threads, substantially as set forth.

2. A coupler or thread-protector formed with an annular body portion having a series of ribs on its inner face, said ribs having screw- 70 threads formed thereon, substantially as set forth.

Signed by me at Pittsburg, Pennsylvania, this 30th day of July, 1898.

GEO. H. HARVEY.
